UNITED STATES PATENT OFFICE.

GEORGE E. KOTHE, OF LANCASTER, MINNESOTA.

GIN-POLE.

1,182,387.

Specification of Letters Patent. Patented May 9, 1916.

Application filed August 17, 1915. Serial No. 45,947.

To all whom it may concern:

Be it known that I, GEORGE E. KOTHE, a citizen of the United States, and resident of Lancaster, in the county of Kittson and 5 State of Minnesota, have invented certain new and useful Improvements in Gin-Poles, of which the following is a specification.

My invention relates to new and useful improvements in gin poles which serve as 10 an adjustable boom from which to suspend a hoisting load line, such as are employed in construction work and particularly in handling and placing structural steel pieces in position.

15 The purpose of the invention is to produce an improved form of gin pole, with suitable attached parts and adjustable supporting lines, which may be employed to advantage in the assembling and construction 20 of towers, buildings, bridges, &c., of various kinds and heights, and particularly to provide a novel form of pole whereby little or no structure will be required for the building of a tower, thus materially lessening the 25 expense of structural work of this sort, and further to design the pole so that it may be used from the ground up and may be used over and over again in the building of not only one, but many towers and which may 30 be raised from time to time and repositioned as the work advances, and finally to provide a pole which can be shifted as suggested with comparatively little trouble and loss of time.

35 With these and other objects in view the invention resides and consists in the construction and novel combination and arrangement of parts hereinafter more fully described, illustrated in the accompanying 40 drawings, and pointed out in the claims hereto appended, it being understood that various changes in the form, proportion, size and minor details of construction within the scope of the claims may be resorted 45 to without departure from the spirit or sacrificing any of the advantages of the invention.

Similar characters of reference denote like or corresponding parts throughout the several figures of the accompanying drawings forming a part of this specification, and upon which,

50 Figure 1 shows a side view of my improved form of gin pole suspended as in 55 operation in a four legged steel structure,

or tower, in the course of construction. Fig. 2 is an enlarged, broken, longitudinal section of the gin pole illustrated in Fig. 1. Fig. 3 shows a cross section taken on line 3—3 of Fig. 2 and Fig. 4 illustrates a similar cross section of a tower having three eyes for the attachment of the supporting lines.

In the drawing I have preferably shown my gin pole applied to a four legged structure, it, however, is equally applicable for use in the construction of a three legged tower, or one having a greater number of columns. It will also be obvious that it is 60 useful on towers of any height and can be 65 used from the ground up, in the building of the whole of the tower, and in which case it obviously has to be shifted to higher elevations, from time to time, as the height 70 of the tower increases.

75 Referring to Fig. 1 wherein I have shown a part of a steel structure it will be noted that the legs 6 of which there are four, are formed of a series of vertically disposed 80 columns 7 the abutting ends of which are secured together to form a continuous leg. These columns are placed end to end one on top of the other and the ends are secured together by plates and angles which are riveted in the usual way. The cross pieces 85 or struts 8 are also usually connected at the points of connection of the column sections. Suitable tie rods 9 are also disposed in angular directions from one corner or intersection of the bents and columns of the one 90 side to that of the other. The particular design of the tower, however, is not essential to the application or use of my improved form of gin pole since it can be used upon a tower built on these same general lines 95 whether it be a three, four or more leg structure. The columns, cross girders, tie rods, &c., are usually designed and arranged so as to leave the inside of the tower free 100 or open which structure materially lends itself to the use of my pole and the hoisting of materials up through the inside of the structure.

10 represents the pole proper which as 105 will be noted is preferably formed hollow and of metal in suitable lengths according to the class of work upon which it is to be used. The upper end of the pole as shown is covered with a cap 11 that is secured in position by a bolt 12. A swivel plate 13

having a suitable pocket 14 formed in its under side loosely covers the end of the cap so that the latter together with the pole can be supported and will turn therein. Three or more ears 15 are formed upon the peripheral surface of the swivel plate to receive the hooks 16 upon the pulley blocks 17 of which there may be three or more. Each of these pulley blocks is provided with an adjustable line 18 of suitable length. The outer end portions of the lines are also provided with pulley blocks 19 that are adapted to be secured as by a tie line 20 to the columns, bents or other portions of the steel structure. An eye 21 is also formed integral with the cap secured to the upper end of the pole and like the eyes on the swivel plate serves to support the hook 22 of the pulley block 23. This pulley block serves to accommodate the load line 24 carrying the suspended pulley block 25 and to which the various pieces of the structure are attached from time to time when the same are to be hoisted.

To the lower end of the pole is secured a shoe 26 having a central hole 27 through its lower end portion. This shoe also includes an annular flange 28 having an annular groove 29 formed on its under side. A basket 30 surrounds the shoe and like it includes a central hole 31 which aligns with the hole in the shoe. An annular flange 32 is also formed around the upper end portion of the basket and upon its top face is provided a groove 33 which registers with the groove in the shoe and serves to accommodate a series of balls 34 thus forming a ball bearing between the two parts and whereby the pole is free to turn within the basket. The basket like the swivel plate on the upper end of the pole is provided with a series of three or more eyes 35 through which the hooks of the pulley block 36 pass. Adjustable guide lines 37 are secured to these blocks and are in turn threaded through the upper blocks 38 which like the blocks 19 attached to the upper guide lines are secured to the structure.

A suitable opening 39 is formed in the side of the lower end of the pole and adjacent to it is mounted rollers 40 over which the adjustable end of the load line 24 to be drawn down along the outside of and out through the holes of the shoe and basket thus serving in a measure to counterbalance the weight of the load carried by the load line and incidentally bringing the adjustable end of the load line down central through the structure where it is less liable to interfere with the hoisting of the steel.

In Fig. 1 my improved gin pole is shown attached to the top of a finished section so to speak. The eight adjustable tie rods being connected to the corners or intersection of the bents and columns. The pole is shown

slightly tilted as in a working position and in the act of supporting a column which is being hoisted to be placed upon and form a continuation of one of the legs shown at the right. The pole can obviously be adjusted so as to be tilted in any direction by simply loosening up on some of the guide lines and tightening on others. In this respect it will be noticed that the blocks of each of the upper lines and the corresponding lower guy lines are arranged close together and secured at substantially the same point or corner of the structure, thus fixing the point of suspension of the lower lines in alignment with the point of connection of the upper guy lines.

In practice as the formation of the structure proceeds and when a section is completed including the placing of the cross girders which connect the upper end of the columns, the guide lines are then shifted one by one from the lower position shown in Fig. 1 and attached to the upper end of the columns in substantially the same manner that they are shown secured below, and in this manner the pole is gradually raised so that its upper end will extend above the structure sufficiently high so that a column can be raised high enough to permit its lower end being placed in position upon the four columns already placed in the structure.

Having thus described my invention what I claim and desire to secure by Letters Patent is:—

1. A gin pole of the class described, the same including a vertically disposed and rotatable pole, and three or more supporting lines attached to each end of said pole.
2. A gin pole of the class described, the same including two end supporting plates, a vertically disposed hollow pole swiveled to turn between the said plates, and three or more supporting lines attached to each of said supporting plates.
3. A gin pole of the class described, the same including a vertically disposed rotatable pole, supporting means in which the poles are mounted to turn, and three or more lines attached to said supporting means.
4. A gin pole of the class described, the same including a hollow pole, having an opening through its lower end, three or more adjustable supporting lines attached to each end, and a load line connected with the top end of the pole and threaded through the hole in the lower end.

5. A gin pole adapted to be suspended from a steel structure, including a pole, supporting members in which the two ends of the pole are swiveled, and three or more adjustable supporting lines attached to each of said supporting members.

6. A gin pole of the class described, the same including a pole, a basket in which it

rests, three or more lines attached to the basket and three or more lines for supporting the opposite end of the pole.

7. A gin pole of the class described, the same including a pole, a basket in which the pole rests, a series of lines for supporting the basket, a swivel attached to the top end of the pole, and three or more adjustable supporting lines attached to the swivel.

10 8. A gin pole of the class described including a vertically disposed pole adapted for movement rotatably, two series of supporting lines the ends of one series being at-

tached to one end of the pole and the end of the other series being attached to the other end, the outer ends of both series being fastened at a point substantially opposite the sides of the pole and a load line carried by the pole.

Signed at Bridgeport, in the county of 20
Fairfield and State of Connecticut this 14th
day of Aug., A. D., 1915.

GEORGE E. KOTHE.
